WILSON GARRISON AND CHARLES H. STEVENS, OF SYRACUSE, NEW YORK.

Letters Patent No. 73,711, dated January 28, 1868.

IMPROVEMENT IN HALTERS.

The Schedule referred to in these Letters Patent and making part of the same.

TO ALL WHOM IT MAY CONCERN:

Be it known that we, WILSON GARRISON and CHARLES H. STEVENS, of Syracuse, in the county of Onondaga, and State of New York, have invented a new and useful Improvement in Halters; and we do hereby declare that the following is a clear, full, and exact description thereof, which will enable those skilled in the art to make and use the same, reference being had to the accompanying drawings, forming part of this specification, in which—

Figure 1 shows the halter complete, and

Figures 2, 3, 4, and 5, are detail views.

Similar letters of reference indicate corresponding parts.

This invention consists in a new and improved construction of metallic joints or connections for uniting the various parts of a halter or headstall for animals, whereby a saving of labor is made, and the greatest facility for incidental repairing is obtained, as hereinafter explained.

In the accompanying drawings, A, in fig. 1, is the crown-strap, B the cheek-strap, E the chin-strap, C the throat-latch, D the nose-strap, F the jowl-strap, and G is the halter. We secure the halter to its ring by means of two plates, H H', fig. 2, which are so formed, that when placed together and secured to the end of the halter, they form a metallic eye (H, fig. 1,) for connecting the halter to its ring. The plate H is cast with several small holes, h h, and the opposite plate, H', with a corresponding number of small pins, h' h', so that when the end of a leather strap is punctured with a like set of holes, the pins h' may be passed through it, and the two plates brought together, as shown by edge view, fig. 2, and secured by a screw, J, which occupies the holes i i. The small pins h' reach through the leather, into the holes of the opposite plate, and by this means a strong hold of the leather is obtained. The screw J also clamps the plates firmly upon the leather, and increases their grasp. A rivet may be employed in place of this screw, but the screw allows the joint to be removed readily, for repairing the halter at any time, and in this respect has advantage over a rivet. The plate H is provided with a sharp transverse rib or nib, j, which engages with a corresponding cavity in the opposite plate H', so that the plates are secured to each other in a more substantial manner than by the pins alone.

Fig. 3 shows an elbow-connection, K, for securing the nose-strap to the cheek-strap. The plates of this connection are secured to the leather, and to each other, in the same manner as in fig. 2, but the back plate is, in this case, made up of two parts, l l, and the main plate K has an eye, k, cast in it, for receiving the chin-strap E, fig. 1.

Fig. 4 shows a metallic connection, M m, for uniting the throat-latch C with the cheek-strap B, with a buckle combined. This connection is made in two parts, M m, which are fastened together upon the leather, as in the preceding connections, and the frame P of the buckle is cast upon the plate M, as shown. The tongue R is also of cast malleable metal, and is cast with a cross-bar, r r. This cross-bar insures a sharp turn of the strap A, (as seen in edge view, fig. 4,) which gives the buckle a stronger hold of the strap, and also strengthens the tongue R, to prevent bending. The eye of the tongue R is cast open, and then bent around the wrist t, but is cast with a shoulder, s, (detached view, fig. 4,) so that the tongue has a fair downward-bearing surface to present to wrist t, for sustaining the increase of downward pressure on the tongue, caused by pressure of the strap on the cross-bar.

Fig. 5 shows the chin-strap buckle P', cast with a securing-plate, for attaching it to its strap, in the same manner as in the other cases.

The loops o are all secured by being clamped in between the plates, and no stitching is necessary for any part of the halter. Rivets may be used in place of the screws J, to hold the plates engaged, but we consider the screws as the most preferable, as it is desirable to have the connections so constructed that little mechanical skill is required to take the connections apart and make repairs, by substituting new straps in place of those which have become worn by use. These metallic connections are all made of cast malleable metal, and the labor and leather saved—thirty inches of leather is saved—in putting the halter together in this manner, more than pays the cost of the connecting-plates, so that we obtain a halter of more neat and finished appearance, with less cost, than by the ordinary method of construction.

Having thus described our invention, what we claim as new, and desire to secure by Letters Patent, is—

1. The metallic eye H , constructed by two hooked plates being clamped upon each other, and upon their strap, substantially in the manner and for the purpose set forth.
2. The method of securing the opposite parts of the metallic connections to each other, and to their straps, namely, one plate provided with pins or projections, h' , and the opposite plate with corresponding holes, h , in connection with a binding-screw or rivet, J , as and for the purpose set forth.
3. The transverse rib j , with corresponding recess in the opposite plate, at the junction of the plates, as herein shown, and for the purpose described.
4. The combination of buckle P' with the double securing-plate $M m$, as herein shown, and for the purpose described.
5. The cross-bar r , substantially as and for the purpose set forth.
6. In connection with the cross-bar and tongue $r R$, the shoulder s , to improve the downward-bearing surface of the tongue, substantially in the manner described.

The above specification of our invention signed by us, this 22d day of November, 1867.

WILSON GARRISON,
CHARLES H. STEVENS.
